CLAIM

We claim the ornamental design for an undergarment with pouch, as shown and described.

DESCRIPTION

FIG. 1 is a front, top, and left side perspective view of an undergarment with pouch;

FIG. 2 is a rear, bottom, and right side perspective view thereof;

FIG. 3 is a top view thereof;

FIG. 4 is a bottom view thereof;

FIG. 5 is a left side view thereof;

FIG. 6 is a right side view thereof;

FIG. 7 is a front view thereof; and,

FIG. 8 is a rear view thereof.

The broken lines in the drawing show portions of the article, including stitching, that form no part of the claimed design.
